UNITED STATES PATENT OFFICE.

ISSACHAR SCHOLFIELD, OF DUNLAP, ASSIGNOR OF ONE-HALF HIS RIGHT
TO BENJAMIN F. FREDRICK, OF MARSHALL COUNTY, IOWA.

IMPROVEMENT IN MIDDLENS-PURIFIERS.

Specification forming part of Letters Patent No. **145,906**, dated December 23, 1873; application filed
August 16, 1873.

To all whom it may concern:

Be it known that I, ISSACHAR SCHOLFIELD, of Dunlap, in the county of Harrison and State of Iowa, have invented certain new and useful Improvements in Middlings-Purifiers; and I do hereby declare the following to be a full, clear, and exact description thereof, reference being had to the accompanying drawings and to the letters of reference marked thereon.

My invention relates to that class of machines used for purifying middlings; and it consists in the construction and novel arrangement of parts, as will be hereinafter more fully set forth.

In order to enable others skilled in the art to which my invention appertains to make and use the same, I will now proceed to describe its construction and operation, referring to the annexed drawings which form a part of this specification, and in which—

Figure 1 is a longitudinal vertical section, Fig. 2 a side elevation, and Fig. 3 a plan view, of my machine.

A represents the frame, which is constructed in any suitable manner to contain the various working parts of my machine. B represents the hopper, in the bottom of which is a longitudinally-fluted or corrugated revolving roller, C. Attached to the hopper B is a feed-board, D, adjusted by means of set-screws *a*, to regulate the feed. E represents a frame or shoe supported upon steel springs H H, and containing or carrying a gang of sieves, G G. This frame E, with its sieves, is vibrated back and forth by means of a pitman, I, one end of which is attached to a crank-shaft, J, and the other end to a cross-bar in the top of the frame. At each backward motion the frame E strikes a bumper, b, formed of a set-screw, which may be adjusted so as to make the blow great or small, as desired. At suitable points through the sieves G G pass bolts *d*. These bolts pass through pieces of leather *e e* glued to each side of each sieve, and through blocks *f f*, placed between the sieves, and are firmly secured by burs on the lower ends under the sieves. On the head of each bolt *d* strikes a hammer, K, which is pivoted at X, as shown

in Fig. 1, and is operated by means of a pin, *i*, projecting from the side of a wheel, L, firmly secured on a revolving shaft, *h*. In each revolution of the shaft *h* the pins *i i* strike projections on the rear ends of the hammers, raising their front ends up, and, as soon as the pins have cleared said projections, the hammers fall down on the heads of the bolts *d d*. *m* is a set-screw attached to the side of the frame E, and passing through the tail-board *n* to raise and lower the sieves at will. Under the sieve-frame E is a hopper-shaped receptacle, M, with a conductor, O, at the bottom. Immediately back of this and under the tail-board *n* is a passage, N, with a conductor, O¹, at the bottom. At the back end of the machine is a chimney, P, with conductor O² at the bottom. The conductor O¹ connects with an elevator, R, at the side of the machine, and at the top of this elevator is a spout, *p*, leading into the hopper B. The chimney P is for the purpose of carrying off dust, &c. At the front part of the machine is the fan-case S, containing the fan T, and the air is forced by said fan through an upwardly-inclined passage, V, to and under the sieves. At each end of the fan case or drum S is a slide, *s*, to regulate the draft.

The operation of the machine is as follows: The middlings are fed into the hopper B and carried over by the fluted roller C, falling onto the gang of sieves G, the pure middlings passing through the sieves into the conveyer O. The impurities are carried over and off the tail-board *n* and fall into the conveyer O², while the returns, or that part of the middlings that may pass over the sieve under the tail-board, fall through the passage N into the conveyer O¹, and are returned by the elevator R into the hopper to be cleaned over.

The separation is effected in the following manner: The pressure of air by the fan T, under and through the gang of sieves G, holds up and forces back the light and impure particles from passing through, and which are carried off over the tail-board *n*, while the pure middlings, being heavier, pass through the sieves into the conveyer O. The separation is also assisted by the vibration of the sieves by the pitmen I, by the hammers K

striking the heads of the bolts *d* in the sieve-cloth, (freeing the cloth from any particles that may adhere to it and prevent them from clogging;) also by the bumper *d*, which causes a sudden jar to the sieves on their backward motion, thus most perfectly separating and carrying off all the impurities.

The various parts of this machine are revolved by means of belts and pulleys, arranged in any suitable manner.

I claim—

1. The combination, with the sieves *G* and hammers *K*, operated as described, of the fan *T*, receptacle *M*, passage *N*, and chimney *P*, with their respective conductors *O* *O*¹ *O*², the

elevator *R*, and spout *P*, arranged in a relative position to each other, substantially as shown and described.

2. In a middlings-purifier, sieves *G*, having pieces of leather *e* glued to each side of each sieve-cloth, and blocks *f* placed between said leather and sieves and firmly secured by means of bolts *d* passing through said parts, in combination with hammers *K*, as and for the purpose mentioned.

ISSACHAR SCHOLFIELD.
